UNITED STATES PATENT OFFICE.

JOHN F. W. DORMAN, OF BALTIMORE, MARYLAND.

PRINTING-PRESS.

SPECIFICATION forming part of Letters Patent No. 373,649, dated November 22, 1887.

Application filed August 13, 1886. Serial No. 210,760. (No model.)

To all whom it may concern:

Be it known that I, JOHN F. W. DORMAN, of the city of Baltimore, and State of Maryland, have invented certain Improvements in 5 Printing-Presses, of which the following is a specification.

The first part of the said invention relates to improved means for holding the platen and rocker firmly in place while the impression is 10 being made, in order to counteract the tendency of the platen to tilt when the type or form is placed either above or below the center of the bed.

The second part of the said invention relates to the combination of the inking-rollers, 15 the inking-disk, and an ink-distributing roller, which is adapted to have a vibratory endwise motion as it passes over the inking-disk to break up and evenly distribute the ink thereon.

In the drawings forming a part hereof, Figure I is an exterior side view of the improved printing-press with certain parts thereof removed. Fig. II is an exterior rear view of the 25 same. Figs. III to XIV, inclusive, are details of the invention, as hereinafter described.

In the said drawings, A is the frame of the press, and A' the driving-shaft to which power is applied. The shaft A' extends entirely through the frame A, and is provided 30 with a fly-wheel, B, (shown only in Fig. I,) and a driving-pulley, which is not represented in the drawings. The press is also provided with a treadle and suitable connections, where- 35 by it can be operated by foot-power, if desired.

At the end of the shaft A' is a pinion, a, which engages with a large wheel, B', on the shaft a'.

40 C is a shaft from which the inking-rollers receive their motion, and the said shaft derives its movement from the shaft a', through the medium of the pair of gears b and b', which are of common or uniform size and fastened, 45 respectively, to the shafts a' and C.

C' is the bed of the press, and its face is denoted by c, and D is the platen, which in general construction differs in no essential particulars from those commonly employed in 50 printing-presses.

D' is the front shaft or spindle extending through the body of the rocker D" and adapted

to be turned therein. The ends of the front shaft or spindle, D', are reduced in size and made eccentric with reference to the center 55 portion thereof. (See particularly Figs. VI and VII.) The eccentric ends of the spindle or front shaft are united to the pins c' c' on the gears B' and b by means of the draw-bars d d. Where the draw-bars are united to the pins c' 60 c', I employ grooved cams and provide the draw-bars, which are slotted, with pins which enter the said grooves to effect a stop in the motion of the platen, as is common.

To throw off the impression it is necessary 65 to turn the front shaft so as to bring its eccentric ends toward the bed of the press, which has the same effect as if the draw-bars were lengthened, as will be readily understood. To obtain this movement of the front shaft I employ a handle, e, (shown in Figs. X, XI, and XII,) the hub of which is secured to the front shaft in any suitable manner. At the rear side of this handle I hinge a lever, e', having a tooth, f, projecting from one of its sides, 70 adapted to bear on the edge of a collar, f', which is attached immovably to the rocker. (See Fig. XI.) A spring, g, is fastened to the outside of the hub of the handle e and bears 75 on the lever e' to keep the tooth f closely in contact with the periphery of the collar f' and make the same enter the notches g' g' in the said collar. By means of these simple devices I am enabled to effect the same result as is usually obtained by the combination of a 80 large number of parts, thus cheapening and 85 simplifying the press.

F is a bar which extends across the frame A, to which it is fastened in any suitable manner. The rocker D" is furnished with two extensions, h h, which pass under the bar F, and 90 where the said extensions are in contact with the said bar they are fitted with steel plates i, fastened thereto by means of screws i'.

When, in the operation of the press, the contact-surfaces of the extensions of the platen and the bar F become worn, the lost movement can be taken up by merely inserting between the steel plates and the extensions h thin pieces of paper, metal, or other substance. 95

A rod, j, confined between the extensions h h of the rocker D", is united, by means of an extensible bar or connecting-rod, F', to the bar F, which is made cylindrical at that point, 100

so that the bifurcated ends of the said rod may turn thereon. This extensible rod is in two parts, *k* and *l*, the former passing within the latter, and is provided with a spring, *l'*, which is confined between a nut on the end of the section *k* and the projecting edge of the section *l*, formed by enlarging the opening therein which holds the spring *l'*. (See Fig. XIV.)

The object in making the rod *F'* extensible 10 will be hereinafter explained. The rocker *D'* is driven forward and backward by means of the draw-bars *d d*, and the lower part of the rocker is united to the fixed bar *F* by means of the connecting-rod *F'*. Consequently the 15 rocker and platen, in their backward motion, are tilted to admit of the placing on the platen the sheets to be printed. In this tilting motion the platen rocks on the curved wings *m*, which bear on the frame *A*. The faces of the 20 extensions *h h* are notched, in order that the platen when forced up to the bed may fit around the rod *G*, as shown particularly in Fig. VI.

It will be understood that the position of 25 the rod *G* is such that it does not interfere with the full approach of the rocker toward the bed of the machine; or, in other words, when the rod is in the notch, the rocker is fully up to its place, and while the bottom of 30 the said slot does not bear with any force on the rod *G*, the edges of the said slot at the face of the rocker prevent the said rocker from tilting, as will be understood. When the rocker is in this position, it is held firmly 35 by the rod *G* and the bar *F*, and no tilting motion can possibly take place, as pressure is applied to the platen.

I am aware that various locking devices 40 have been employed to prevent the tilting of the platen when the impression is being made; but in all of them there is great liability to wear of the frictional surfaces. In my improved press the locking devices can only wear at the point where the extensions *h h* of the platen 45 are in contact with the bar *F*, and this can be easily compensated for by the insertion of liners between the steel plates and the extensions, as hereinbefore described. It will be seen that there can be no wear or friction 50 where the notched platen passes around the rod *G*, as the surfaces of the said parts are merely brought together. In the backward movement of the draw-bars *d d* the spiral spring *l'* in the connecting-rod *F'* is compressed 55 and the platen rocks, as before described.

H is an inking-disk, which is revolved in the usual manner, and therefore the means for effecting its revolution require no description 60 herein. The said inking-disk is provided with a brake, which consists of a headed stem, *n*, having at its upper end a wooden plug to bear against the under side of the disk to cause friction, and a spring, *o*, to keep the said stem 65 extended. This brake serves to effect a regu-

lar tension on the inking-disk, and prevents the same being carried around farther than the distance traveled by the pawl *p*.

The inking-rollers are denoted by *I*, and the arms through which they receive their backward and forward movement by *J*. The said arms oscillate on the shaft *a'*, and the motion is derived from a crank, *K*, forming a part of the shaft *C*, through the medium of the connecting-rod *L*. 75

M is an ink-distributing roller supported by the arms *J* and sliding stems and springs, in a manner similar to the inking-rollers *I*. It differs, however, from them in that its roller-wheels are of such size as to prevent the said 80 roller coming in contact with the type, while they permit it to roll on the inking-disk. The roller-carriers *N*, which support the distributing-roller, are fitted with helical collars or cams *O*, and the core or spindle *P* of the said roller is 85 furnished with pins *q*, which bear against the faces of the said cams. These pins project from opposite sides of the roller core or spindle. Consequently, in the revolution of the distributing-roller, the same receives a reciprocating endwise motion as it passes over the 90 ink-disk, and the ink is evenly distributed.

It will be understood that to make the vibratory ink-distributing roller thoroughly effective it is necessary that the ink-disk should 95 have a regular motion, and this is effected by the brake before described. With these two devices combined a result is produced equal in all essential particulars to the more complicated and costly devices now in use. 100

I am aware that rotative inking-disks have been used in connection with inking-rollers placed in an angular position with reference to a line at a right angle with the general path of the said rollers, the same having a vibratory movement in view of their angular position and the action of the inking-surface; but in this arrangement the ink on the surface of the ink-disk is only carried over in the form of a wave in one direction as the roller passes 110 up, and in a contrary direction as it is reversed or passes down. With my invention the roller is moved backward and forward in an endwise direction on the rotative inking-disk as it travels either way, cutting and 115 distributing the ink more effectually than it is possible with the self-vibratory roller above alluded to.

I do not claim, broadly, the combination of a rotative inking-disk and a vibratory distributing inking-roller; but 120

What I do claim as my invention is—

1. In a printing-press, the combination of the platen *D*, having the extensions *h*, the fixed bar *F*, and the rod *G*, the said extensions 125 being notched to fit around the said rod, substantially as and for the purpose specified.

2. In a printing-press, the combination of a rotating inking-disk and an ink-distributing roller adapted to pass over the said disk, 130

the same being adapted to make a full or complete endwise vibration at each revolution, substantially as and for the purpose specified.

3. In a printing-press, the combination of 5 a rotating inking-disk, an ink-distributing roller supported by means of its spindle in the inking-roller arms, transverse pins projecting laterally or radially from the said spindle near to its ends and in opposite directions, and 10 helical collars rigidly attached to the faces of

the said inking-roller arms, and between the said arms and the said radially-situated pins, whereby, in the rotation of the said distributing-roller, the same is made to vibrate endwise on the inking-disk, substantially as and for 15 the purpose specified.

JOHN F. W. DORMAN.
